WIRE HOLDER

Homer H. Hummel, Warrenton, Mo., assignor to
 James B. Kearney Corporation, St. Louis, Mo.,
 a corporation of Missouri

Application September 16, 1940, Serial No. 356,937

7 Claims. (Cl. 24—136)

This invention relates generally to wire holders of the type employed to mechanically attach drop, lead-in, and other service wires to houses, buildings, or other structures, and more specifically to such a wire holder which is of such improved and unique construction and arrangement that various disadvantages incident to the use of wire holders of the types formerly employed for this purpose are eliminated, the predominant object of the invention being to provide an improved wire holder of simple and inexpensive construction which holds a wire to a considerable extent in accordance with the snubbing principle instead of through the use solely of clamping pressure applied to the insulation of the wire, as was frequently the case heretofore.

Fig. 1 is a plan view of the improved wire holder showing same in association with a wire.

Fig. 2 is a side elevation of the assembly illustrated in Fig. 1.

Fig. 3 is an end elevation of the structure illustrated in Figs. 1 and 2 with portions of the wire shown in section.

Fig. 4 is a section taken on line 4—4 of Fig. 2.

Fig. 5 is a vertical section of the improved wire holder with the wire omitted and with a portion of the bail broken away.

In the drawing, wherein is shown for the purpose of illustration, merely, one embodiment of the invention, A designates the improved wire holder generally. The wire holder A includes a main body portion 1 which may be produced from any suitable material, such as metal, or, if preferred, said main body portion may be made from a suitable electrical insulating material such, for instance, as lava or Bakelite. The main body portion 1 includes a substantially circular portion 1a and an extension 1b which is extended tangentially with respect to said substantially circular portion 1a as shown to the best advantage in Fig. 5.

Formed in the edge portion of the main body portion 1 is a groove 2 which is open at the edge of the body portion and follows the contour of said edge of said body portion; that is to say, the portion 2a of the groove 2 at the substantially straight, upper portion of the extension 1b is substantially straight and merges into a curved portion 2b of the groove which follows around the curved edge portion of the substantially circular portion 1a of the body portion 1. The curved portion of the groove 2 merges with a substantially straight groove portion 2c which is disposed at an approximate right angle with respect to a straight groove portion 2d which is

formed in the lower portion of the extension 1b. It is to be noted that the groove 2, from the outer end of the extension 1b to the point designated by the reference character 2x is of the approximately semi-circular cross-sectional shape shown at the upper ends of Figs. 3 and 4, while the portion of the groove extended from the point 2x throughout the lower portion of the substantially circular portion 1a of the body portion has the tapered cross-sectional shape shown at the lower portion of Fig. 4. The right angle portions 2c and 2d of the groove 2 are of substantially rectangular cross-sectional shape as shown at the intermediate portion of Fig. 3. 15 The improved wire holder A includes also a bail 3 which is formed from a length of wire, or other suitable material, and is bent double to provide a loop at the outer end of the bail as shown to the best advantage in Fig. 1. When 20 viewed in side elevation the bail is shaped as shown in Fig. 2 and the opposed, angular portions 3' of said bail are extended longitudinally through grooves 4 which are formed in the opposed outer faces of the main body portion 1. 25 As shown in Figs. 2 and 5 the grooves 4 are inclined downwardly with respect to the top edge of the body portion 1, from points adjacent to a point where the top edge of the extension 1b merges into the curved edge of the substantially 30 circular portion 1a of said body portion, to points adjacent to the junction of the straight, right angle groove portions 2c and 2d, said grooves 4 being open at their opposite ends. The grooves 4 are of the cross-sectional shape shown in Fig. 35 4; that is to say each of said grooves includes a narrower lower portion which is closed at its outer side by a lip 4' forming a part of the main body portion 1 and above said lips 4' the grooves are open at the opposite sides of the main body 40 portion 1 to permit entrance into the grooves of the opposed, angular portions 3' of the bail 3. Secured to the lower end portions of the opposed, angularly extended portions 3' of the bail 3 is a clamping member 5 which is preferably of 45 approximately triangular shape. The clamping member 5 is disposed in the crotch of the right angle groove portions 2c and 2d and is provided with a curved portion 4a which joins the straight faces 4b and 4c of said clamping member. The clamping member 5 is connected to the angularly extended portions 3' of the bail 3 by forming an opening transversely through said clamping member and introducing into and fixing in said opening a tubular element 6 which 50 is elongated in cross-section. The end portions 55

of the portions 3' of the bail 3 are bent at right angles, as shown at 3a in Fig. 3, and are passed in opposite directions through the tubular element 6 after which the extreme end portions of said portions 3a are upset as shown at 3b to lock said bail portions 3a and the clamping member 5 in their related positions.

In applying the improved wire holder to a wire, such as the wire W shown in the drawing, the unit comprised of the bail 3 and the clamping member 5 is removed from the body portion 1 of the wire holder. This may be accomplished by moving the body portion 1 rearwardly of the bail, which at this time is straight, until the body portion moves into the wider looped end portion of the bail. As the body portion moves into the wider portion of the bail the opposed leg portions of the bail pass from the grooves 4 whereby the body portion is detached from the bail. When the body portion has been detached from the bail as described the wire W is looped about said body portion at the desired point, the wire being drawn deep in the groove 2, and the wider loop portion of the bail is passed over the substantially circular portion 1a of the body portion 1 to position the opposed leg portions of the narrower portion of the bail in line with the grooves 4 of the body portion. The bail is then moved with respect to the body portion of the wire holder to cause the opposed leg portions of the bail to move into the grooves 4 and to bring the clamping member 5 into contact with the wire at the locations of the right angle groove portions 2c and 2d. The bail is then bent as required, and as shown in Fig. 2, and the looped outer end of the bail is secured to the house, building, or other support by suitable attaching means (not shown).

It is to be noted that a wire secured to a support by means of the improved wire holder disclosed herein is held by combined snubbing and pressure clamping actions. In other words the portion of the wire which passes about the substantially circular portion 1 of the body portion of the wire holder is held by snubbing action, while the portions of the wire which are engaged between the faces 4b and 4c of clamping member 5 and walls of the right angle groove portions 2c and 2d are held by pressure clamping action. Also it is important to note that the wire holding forces resulting from the snubbing and pressure clamping actions referred to are in proportion to, and increase and decrease in accordance with, the pull on the wire. This result is a natural consequence of the snubbing action obtained in connection with a portion of the wire and follows from the fact that increased pull on the wire will cause the clamping member 5 to grip the wire with increased pressure. Additionally increased gripping action between the body portion of the wire holder and the wire is obtained because a portion of the groove 2 is of tapered cross-sectional shape as shown at the bottom of Fig. 4, as the wire is wedged deep in the tapered portion of the groove 2 by pull on the wire and hence is securely gripped by said body portion of the wire holder.

By employing grooves 4 of the cross-sectional shape shown in Fig. 4, the lips 4' prevent accidental displacement of the opposed bail portions from the grooves as the pull on the bail will draw said opposed bail portions into the narrow, lower portions of the grooves and behind said lips.

If desired the substantially circular portion 1a

of the body portion 1 may be an opening 7 formed transversely therethrough. This opening serves to reduce the weight of the body portion and also the drop portion W' of the wire W may be passed through said opening to facilitate a change in the direction of extension of said drop portion of the wire.

I claim:

1. A wire holder comprising a body portion having a portion adapted to receive in snubbing relation therewith a portion of a wire held by said wire holder, a clamping member adapted to clamp a portion of a wire held by the wire holder between said clamping member and a part of said body portion, and a bail attached to said clamping member and adapted to be connected to a support, said bail being provided with opposed inclined portions and said body portion having inclined grooves formed at opposite faces thereof in which said opposed inclined portions of the bail are seated.
2. A wire holder comprising a body portion having a portion adapted to receive in snubbing relation therewith a portion of a wire held by said wire holder, a clamping member adapted to clamp a portion of a wire held by the wire holder between said clamping member and a part of said body portion, a bail attached to said clamping member and adapted to be connected to a support, said bail being provided with opposed inclined portions and said body portion having inclined grooves formed at opposite faces thereof in which said opposed inclined portions of the bail are seated, and means at said grooves for preventing unintended displacement of said opposed inclined portions of the bail from said grooves.
3. A wire holder comprising a body portion having a portion adapted to receive in snubbing relation therewith a portion of a wire held by said wire holder, a clamping member adapted to clamp a portion of a wire held by the wire holder between said clamping member and a part of said body portion, a bail attached to said clamping member and adapted to be connected to a support, said bail being provided with opposed inclined portions and said body portion having inclined grooves formed at opposite faces thereof in which said opposed inclined portions of the bail are seated, and means at said grooves for preventing unintended displacement of said opposed inclined portions of the bail from said grooves, said means comprising projected lip portions formed on said body portion which close portions of said grooves at their outer sides.
4. A wire holder comprising a body portion having a portion adapted to receive in snubbing relation therewith a portion of a wire held by said wire holder, said body portion having a groove formed in the marginal edge portion thereof which receives the wire, a clamping member adapted to clamp a portion of a wire held by the wire holder between said clamping member and a part of said body portion, and a bail attached to said clamping member and adapted to be connected to a support, said bail being provided with opposed portions and said body portion having grooves formed at opposite side faces thereof in which parts of said opposed portions of the bail are seated, the groove of said body portion including as a part thereof a substantially rectangular portion into contact with which the clamped part of a wire held by the wire holder is forced by said clamping member.

5. A wire holder comprising a body portion having a portion adapted to receive in snubbing relation therewith a portion of a wire held by said wire holder, said body portion having a groove formed in the marginal edge portion thereof which receives the wire and a part of which groove is of tapered cross-sectional shape wherein a part of the wire is adapted to be wedged, a clamping member adapted to clamp a portion of a wire held by the wire holder between said clamping member and a part of said body portion, and a bail attached to said clamping member and adapted to be connected to a support, said bail being provided with opposed portions and said body portion having grooves formed at opposite side faces thereof in which parts of said opposed portions of the bail are seated, the groove of said body portion including as a part thereof a substantially rectangular portion into contact with which the clamped part of a wire held by the wire holder is forced by said clamping member.

6. A wire holder comprising a body portion having a portion adapted to receive in snubbing relation therewith a portion of a wire held by said wire holder, said body portion having a groove formed in the marginal edge portion thereof which receives the wire and a part of which groove is of tapered cross-sectional shape wherein a part of the wire is adapted to be wedged, a clamping member adapted to clamp a portion of a wire held by the wire holder between said clamping member and a part of said body portion, a bail attached to said clamping member and adapted to be connected to a support, said bail being provided with opposed portions and said body portion having grooves formed at opposite side faces thereof in which parts of said opposed portions of the bail are

5 seated, and means at said grooves at the opposite side faces of said body portion for preventing unintended displacement of said parts of said opposed portions of the bail from said grooves, the groove of said body portion including as a part thereof a substantially rectangular portion into contact with which the clamped part of a wire held by the wire holder is forced by said clamping member.

10 7. A wire holder comprising a body portion having a portion adapted to receive in snubbing relation therewith a portion of a wire held by said wire holder, said body portion having a groove formed in the marginal edge portion thereof which receives the wire and a part of which groove is of tapered cross-sectional shape wherein a part of the wire is adapted to be wedged, a clamping member adapted to clamp a portion of a wire held by the wire holder between said clamping member and a part of said body portion, a bail attached to said clamping member and adapted to be connected to a support, said bail being provided with opposed portions and said body portion having grooves formed at 15 opposite side faces thereof in which parts of said opposed portions of the bail are seated, and means at said grooves at the opposite side faces of said body portion for preventing unintended displacement of said parts of said opposed portions of the bail from said grooves, said means comprising projected lip portions formed on said body portion which close portions of said grooves at their outer sides, the groove of said body portion including as a part thereof a substantially rectangular portion into contact with which the clamped part of a wire held by the wire holder is forced by said clamping member.

HOMER H. HUMMEL.
